METHOD OF DRIVING SHEET PILING

August H. Hausler, Chicago, Ill.

Application May 14, 1934, Serial No. 725,491

14 Claims. (Cl. 61—34)

This invention relates to improvements in methods of driving sheet piles in rivers, harbors and the like for the purpose of forming enclosures such as those of breakwaters, caissons, coffer-dams and the like. It has heretofore been the common practice to form such structures by driving interlocking sheet piles to form the desired enclosures which are then filled with crushed rock or other ballast to give the structure the desired weight and stability, but the former practice has presented great difficulty because of the fact that sheet piles are necessarily of considerable length in order to extend downwardly through the water and into the bed of the river or harbor, making it necessary to elevate each sheet pile to a considerable height in order to interlock it with its neighboring pile at the beginning of the driving operation. It is difficult to hold the piles at such a high elevation and the contour of the wall of the enclosure cannot be formed with accuracy when they are thus put in place successively, because of the effect of wind and water.

The present invention overcomes the foregoing difficulties by providing a new method of construction according to which a series of sheet piles are placed in interlocking relation with each other on the shore, or elsewhere, and are then moved bodily to the place where they are to be driven. The section of connected sheet piles forms a panel which is put in position with one end of the section resting on the bottom of the river or harbor and this section is connected by spacing devices with other similar sections or panels with the result that they are all properly located in vertical positions substantially completing an enclosure of the desired form, after which the spacing devices then are removed and each pair of adjacent sections is connected by putting an interlocking sheet pile in place, thus completing the enclosure, preliminary to driving all of the piles which form the enclosure. An important feature of the invention is the provision of an improved method of construction according to which all of the sheet piles which make up a unit of the breakwater or other structure are put in place to form an enclosure before they are driven. A further important feature of the present invention is the provision of spacing devices or distance pieces which are employed to connect the end pile of each section or panel with the end pile of the next adjacent section during the process of putting the sections in place and spacing them apart to receive an intermediate connecting interlocking pile which may be put in place when the spacing devices are removed. A further ob-

ject of the invention is to provide a detachable spacing device which may be employed to space two piles apart, or two series of connected piles, in order that the piles connected by the spacing devices will be accurately spaced apart throughout their length before being driven so that a connecting pile can then be put in place after removal of the spacing devices. Another object of the invention is to provide improved means for connecting a group of removable piles together to form a panel while they are being moved from the place of assembly to the place where they are to be driven and for imparting to the panel the desired shape or curvature. Still another object of the invention is to provide a new method of construction of breakwaters, coffer-dams and the like according to which the final structure is made up of a series of connected enclosures, each enclosure comprising a plurality of wall sections formed of interlocking sheet piles, these wall sections being put in place around a floating raft which forms a template to determine accurately the form of the sectional enclosure. A further object of the invention is to provide an improved detachable guide, one or more of which may be put in place upon the upper end or ends of adjacent piles at the ends of two sections or panels, to guide a connecting pile at the beginning of the operation of driving the connecting pile. Other objects relate to various features of construction and arrangement which will appear more fully hereinafter.

The nature of the invention will be understood from the following specification taken with the accompanying drawings in which one example of the improved apparatus of the present invention and one example of the improved method of construction are illustrated.

In the drawings,—

Fig. 1 shows a top plan view of a portion of a breakwater constructed according to the principles of the present invention, showing the last section of the breakwater in the process of construction.

Fig. 2 shows a longitudinal vertical section taken on the line 2—2 of Fig. 1.

Fig. 3 shows an enlarged vertical section taken on the line 3—3 of Fig. 1.

Fig. 4 shows an enlarged elevation of the end portions of two piles which constitute the end piles of two adjacent pile sections, these piles being spaced apart by the enclosed spacing device of the present invention in order that these piles may receive a connecting sheet pile shown above the spacing device.

- Fig. 5 shows a section taken on the line 5—5 of Fig. 4.
- Fig. 6 shows a vertical section taken on the line 6—6 of Fig. 4.
- 5 Fig. 7 shows an enlarged horizontal section taken on the line 7—7 of Fig. 3, illustrating two of the guide members which are employed for guiding a connecting pile when this pile is driven into interlocking engagement with the end piles 10 of two adjacent pile sections.
- Fig. 8 shows an elevation of one of the guide members illustrated in Fig. 7, together with portions of the adjacent piles;
- 15 Fig. 9 is a perspective view of one of the guide members illustrated in Figs. 7 and 8;
- Fig. 10 shows a top plan view of one of the special piles of Y cross-section which are employed at the points where three wall sections meet;
- 20 Fig. 11 is a perspective view of a bar which may be employed for securing the piles of a panel together to hold the piles in assembled relationship and to give the panel a predetermined form when it is placed on end preliminary to being united with the panels;
- 25 Fig. 12 shows a top plan view of a number of interlocking sheet piles connected by the panel illustrated in Fig. 11;
- Fig. 13 shows an enlarged vertical section on the line 13—13 of Fig. 12; and
- 30 Fig. 14 shows a horizontal plan view, partially in section, illustrating the means for enlarging the opening in one end of one of the spacing devices to permit ready relative movement of an adjacent sheet pile therethrough.
- 35 In Figs. 1 and 2 of the drawings there is illustrated a portion of a breakwater 15 comprising a series of connected sections 15^a, 15^b, 15^c and 15^d, each of which comprises a surrounding wall made up of interlocking sheet piles 16 which are driven 40 into the bed 17 of the river or harbor or other waterway in which the breakwater is formed. A portion of the surrounding wall of each section forms a part of the wall of the next adjacent section and these walls of sheet piling form enclosures 18^a, 18^b, 18^c and 18^d which, when the breakwater is completed, are filled with suitable ballast such as rocks 19 shown filling the enclosure 18^a. The section 15^a of the breakwater at the end of the structure is substantially circular 45 in cross-section, comprising a wall section 20^a which forms the arc of a circle and which extends through about three-quarters of the circumference of the section. The ends of this section are connected by a wall section 20^b which forms the end wall of the next adjacent section 15^b. The other sections 15^b, 15^c and 15^d are alike in construction, each comprising two curved side walls 20^c, which are convexed outwardly, and which are 50 connected at their ends by a transverse end wall 20^b, similar in form and dimensions to the one previously described. Each pile comprises a longitudinal flat web 16^a united at each edge with a curved portion 16^b and these curved portions are 55 united with integrally formed hook members 16^c and curved guard members 16^d. With this construction, there is provided at each edge of the pile a longitudinal groove or recess 16^e which is adapted to be engaged by the hook member of 60 the next adjacent, and reversely arranged, pile 16 when two piles are interlocked with each other. All of these wall sections are made up of interlocking sheet piles 16 and the present invention is directed to the method of and apparatus by which 65 these piles are put in place. Other forms of sheet 70 piling may be used in the practice of the present invention.
- At each point where two of the side walls 20^c are united with one of the transverse walls 20^b, there is provided a specially formed pile 21 of Y cross-section, shown particularly in Fig. 10. This pile comprises three radiating plates 21^a, two of which may be integrally formed, and each plate has a curved portion 21^b united with a hook member 21^c and a guard member 21^d, thus forming a 10 groove 21^e adapted to interlock with the edge of one of the adjacent piles 16. One of the plate portions 21^a which is separately formed, is united with the other plates 21^a by means of connecting plates 21^f and rivets 21^g.
- 15 In order that the piles 16 forming a panel may be held in assembled relationship with respect to each other while the panel is being moved from the place of assembly to the place where the piles are to be driven, and to hold the panel in 20 the desired shape, the various piles making up the panel are preferably secured to a channel-shaped bar 22 which is provided with a series of projecting wedge-bolts 22^a adapted to engage apertures 16^f which are formed in the piles, preferably adjacent the upper ends thereof. The bar 22 is adapted to fit against the webs of alternate sheet piles, as shown in Fig. 12, and when the wedge-bolts 22^a, which are preferably welded 25 to the bar, have been inserted through the apertures 16^f, the wedges or keys 22^b are inserted through slots 22^c in the wedge-bolts, as shown in Figs. 12 and 13, thus holding the sheet piles in place against the bar. The keys 22^b are preferably carried by chains 22^d which are attached 30 to the upper flange of the bar 22 so that the keys are always in readiness for use. After a section or panel of interlocking sheet piling has been put in place, as hereinafter described, the keys 22^b are removed and the bar 22 taken away 35 from the piles, preliminary to driving the piles.
- Assuming that the first three sections 15^a, 15^b and 15^c of the breakwater 15 have been formed according to the method of the present invention, and that the section 15^d is about to be 40 formed, there is first placed against the outer end wall 20^b of the section 15^c a floating raft 23 which may be formed of wood or as a hollow metal structure and which serves as a template about which the sheet piles forming the remaining walls of the section 15^b are to be located and then driven. This raft serves also as a platform upon which workmen may stand during the operation of placing the panels in position and also during the operation of driving the piles, and it 45 is secured to the next adjacent section 15^c by means of tie rods 24 which are secured to plates 50, carried by the raft, and also to the adjacent transverse wall 20^b. These tie rods may be provided with turn-buckles 26 by which their lengths 55 may be adjusted. Having put the raft 23 in place, the next operation is to form the two side walls 20^c and the transverse connecting wall 20^b which extend along the remaining edges of the raft 23. This may be done according to the present invention by assembling part of the sheet piles 16 of one of the side walls 20^c on shore, or upon a dredge or scow, thus forming a panel 20^c made up of a number of sheet piles interlocked 60 with each other and preferably connected by a bar 22 which is curved to correspond with the curvature of the lateral edge 23^a of the raft. When this panel has been formed, it is placed 65 in position along the edge of the raft with the lower edges of the pile resting on the bottom and 70
- 75 75

one or more of the sheet piles which are not bolted to the bar 21 may be driven slightly into the bed of the river or harbor to assist in holding the panel in place. Other panels 20^a for the 5 side walls 20^c are similarly formed and put in place and also corresponding panels for the end wall 20^b which is to be formed along the curved end 23^b of the raft.

When these wall sections or panels are put in 10 place along the edges of the raft 23 with the lower ends of the piles engaging the bed of the river or harbor, they are spaced apart from each other and from the corner piles 21 distances each equal to the width of one sheet pile and they 15 are held in this spaced relation around the raft by means of spacing devices or distance pieces 30 which have the form shown particularly in Figs. 4, 5 and 6. Each spacing device 30 comprises a bar 30^a having formed thereon a pair 20 of bosses 30^b between which are mounted a pair of clamping members 30^c. These clamping members are pivoted on the bosses by means of pins 31 and are provided at their ends with curved portions 30^d which are adapted to extend over 25 and conform to the curvature of the guard members 16^c or 21^c of two adjacent sheet piles. The bar 30^a of each spacing device is provided at each end with a hook shaped portion 30^e which is adapted to extend over and conform to the 30 shape of the outer portion of the hook member 16^c or 21^c of an adjacent sheet pile. When the clamping members 30^c are in closed position, as shown in Figs. 4 and 5, the portions 30^d and 30^e 35 form between them a longitudinal slot or groove adapted to receive both the hook member and the guard member of an adjacent sheet pile while at the same time permitting this pile to be driven. The clamping members 30^c are provided with slots 30^f adapted to be engaged by lugs 32 which 40 are formed on the bars 30^a. These lugs 32 are provided with apertures 32^a which are adapted to be engaged by wedge-shaped pins 33. These pins are secured on the clamping members 30^c by means of chains 34 which are secured to 45 apertured lugs 30^g which are formed on the outer faces of the clamping members. The bar 30^a is reenforced longitudinally by ribs 30^h which extend on opposite sides of the clamping members 30^c when these clamping members are in closed 50 position and the bar 30^a is further reenforced on its other side by a longitudinal rib 30ⁱ to which is secured a handle 35. This handle may be engaged by a rope or chain for supporting the spacing device or lowering it into position 55 where it is applied to the edges of two adjacent sheet piles. The length of each clamping device 30 is such that it spaces two adjacent sheet piles 16, or 16 and 21, the required distance to permit a sheet pile 16 to be inserted after the spacing 60 devices have been removed. If it be desired to form a somewhat loose engagement between a clamping device 30 and the adjacent sheet pile which interlocks therewith, in order to permit the pile to be driven somewhat into the bed of 65 the river or harbor before the clamping device is removed, a shim or washer 36 may be placed over one of the lugs 32, as shown in Fig. 14, thus spacing the adjacent clamping member 30^c away from the body portion of the spacing bar 30^a 70 and the wedge-shaped pin 33 is then only partially inserted into the slot 32^a in the lug. This clamping and spacing device is claimed in my copending divisional application, Serial No. 17, 401, filed April 20, 1935.

75 After the spacing devices 30, which may be

formed of cast, forged or rolled steel, are put in place to space adjacent wall sections or panels from each other and to space the inner side panels from the adjacent corner piles 21, the wall sections conform to the curvature of the edges of 5 the raft 23 and all of the piles occupy vertical positions in readiness for driving. Before these piles are driven, however, the spacing devices 30 are removed by taking out the wedge-shaped pins or keys 33 and releasing the spacing devices 10 which may then be elevated and placed on the raft. As the spacing devices 30 are removed from the region between the two sheet piles connected thereby, another sheet pile 16 is inserted in interlocking engagement with the adjacent sheet 15 piles which have previously been connected by the spacing devices, as indicated by dotted lines in Fig. 3. A sheet pile 16 is inserted in each of these spaces which have been determined by the spacing devices 30, including sheet piles connecting the ends of the innermost side wall sections with the corner piles 21 which have previously been driven and which form a part of the previously formed section 15^c of the breakwater. This operation requires the elevation of the sheet 25 piles 16, which are to occupy these spaces, until their lower ends are capable of engaging the longitudinal grooves of the sheet piles which are to be connected by them and in order to facilitate this operation, a pair of guide members 40 are 30 detachably mounted upon the upper ends of the previously positioned piles for guiding the new pile into interlocking engagement with the piles which are to be connected thereby. These guide members 40 are of the form shown particularly in 35 Figs. 7, 8, and 9 and include right-hand and left-hand guide members for engaging opposite edges of the same sheet pile. Each guide member comprises a horizontal bar 40^a having a handle 40^b projecting from the upper side thereof and having enlargements 40^c at its ends from which project downwardly two pairs of spaced legs 40^d. At one end, the bar 40^a is provided with a hook-shaped member 40^e which conforms to the shape and curvature of the guard members 16^c which 45 are formed upon the sheet pile 16. The guide members 40 are put in position on the upper ends of the previously driven piles 16 with the legs 40^d straddling the portions 16^a and 16^b of the sheet piles. The portions 40^e 50 then are positioned above the guard members of the sheet piles and form stops against which the hook members 16^c of the pile to be driven may be placed, as shown in Fig. 7. Then, upon moving the intervening sheet pile downwardly, the portions 40^e of the guide members 40 serve as guides to direct the hook members 16^c of the pile into engagement with the slots 16^f of the piles at the ends of the panels which have 55 previously been positioned. The initial position of the intervening sheet pile when it is first brought into engagement with the guide members 40 is shown in the upper part of Fig. 3 by dotted lines and as this pile is driven downwardly into engagement with the slots or grooves of the 60 end piles of the panels which have previously been positioned, it forms a permanent connection between the wall sections or panels. The improved guide member described above is claimed 65 in my copending divisional application Serial No. 18,153, filed April 25, 1935.

When all of the spacing devices 30 have been removed and piles 16 have been lowered into interlocking engagement with adjacent piles to 70 close the spaces previously occupied by the spac- 75

- ing devices, there will then be a continuous row of interlocking sheet piles around the edges of the raft 23 with the lower ends of the piles resting on the bottom or driven slightly into the bed of the river or harbor. The parts are then in readiness for driving all of these connected piles further into the bed or harbor until their upper ends are at substantially the same level at the upper ends of the piles which form the walls of the breakwater sections 15^a, 15^b and 15^c, which have previously been constructed. In this way, a surrounding wall for one breakwater section is conveniently formed to provide an enclosure of predetermined contour determined by the form of the raft and all of the piles are so positioned before being driven that they can be driven vertically downward without danger of any of the piles extending at angles to vertical lines, as was the case in the former practice, where the piles were successively interlocked with each other at the place where they were to be driven, and without the necessity of elevating a great number of piles to a point where their lower ends are above the raft, inasmuch as the only piles which need to be thus elevated are those which occupy the spaces initially occupied by the spacing devices 30 and these spaces are so maintained that the piles which are thus elevated and lowered into position may be readily inserted because the edges of the piles with which they interlock are spaced uniformly apart. By the same method of construction, a breakwater of any desired extent may be constructed in the water with a minimum of difficulty and with better results than those which have heretofore been obtainable. When all of the walls of the breakwater sections have been built, they may be filled with stone or other ballast, as illustrated in the case of section 15^a. Although certain examples and embodiments of the invention have been shown and described by way of illustration, it will be understood that the invention may be practiced in various ways and may take various forms coming within the scope of the appended claims.
- 45 I claim:
1. The method of forming a wall of sheet piling which consists in forming a plurality of panels of connected sheet piles, placing said panels in position to be driven with the edges of adjacent panels spaced apart, connecting said edges of adjacent panels, and then driving the piles of said panels.
  2. The method of forming a wall of sheet piling which consists in forming a plurality of panels of connected sheet piles, placing said panels vertically in position to be driven and spacing the adjacent edges thereof apart, inserting sheet piles to connect said adjacent edges, and then driving all of said piles.
  3. The method of forming a wall of sheet piling which consists in forming a plurality of panels of connected sheet piles, placing said panels in position to be driven, connecting the edges of adjacent panels and spacing them apart by detachable spacing devices while said panels are being positioned, then removing said spacing devices and inserting piles to connect the edges of adjacent panels, and then driving all of said piles.
  - 70 4. The method of forming a wall of sheet material which consists in forming a pair of panels of connected sheet piles, placing said panels in vertical position ready to be driven, spacing the adjacent end piles of said panels apart by detachable spacing devices while they are being

placed, and then removing said spacing devices and inserting a sheet pile into interlocking engagement with said end piles.

5. The method of forming a wall of sheet piling which consists in driving one series of sheet piles to form a portion of a wall, forming a panel of connected sheet piles, placing said panel adjacent a pile of said series and spacing it therefrom in readiness to be driven, inserting a pile into interlocking engagement with said last named pile and the adjacent end pile of said panel, and then driving the piles of said panel.

6. The method of forming a wall of sheet piling which consists in putting a series of sheet piles into interlocking engagement with each other to form a panel, securing a bar to said panel to maintain the shape of said panel and to hold said piles in assembled relationship, then placing said panel in position to permit the piles thereof to be driven, and then removing said bar and driving said piles.

7. The method of forming a wall of sheet piling which consists in forming a plurality of panels each consisting of a series of interlocked sheet piles, securing a bar to each of said panels, placing said panels in position to be driven, spacing the edges of said panels apart, inserting sheet piles in said spaces to connect adjacent panels, removing said bars, and then driving the piles of said panels.

8. The method of forming a wall of sheet piling which consists in forming a plurality of panels of connected sheet piles, placing said panels in upright position to form an enclosure, spacing the edges of adjacent panels apart by detachable spacing devices, removing said spacing devices and inserting sheet piles in said spaces to connect adjacent panels, driving said sheet piles, and then filling said enclosure with ballast.

9. The method of forming a wall of sheet piling which consists in forming a series of panels each consisting of a plurality of interlocked sheet piles, applying shaping means to each of said panels to give it a predetermined shape, placing said panels in upright positions to form an enclosure, spacing the edges of adjacent panels apart, inserting sheet piles in said spaces to connect said panels and retain said predetermined shape, removing said shaping means and then driving all of said sheet piles.

10. The method of forming a wall of sheet piling which consists in securing a raft at the place where the wall is to be built, forming a panel of connected sheet piles, securing a bar to said panel to give it a predetermined shape corresponding with an outline of an edge of said raft, then placing said panel in upright position adjacent said edge, removing said bar, and driving the piles of said panel.

11. The method of forming a structure in water which consists in floating a raft upon said water, forming a plurality of panels of interlocked sheet piles, placing said panels in upright position around the edge of said raft, driving the piles of said panels, and then removing said raft from the enclosure formed by said panels.

12. The method of forming a structure in water which consists in floating a raft upon said water, forming a series of panels of connected sheet piles, placing said panels in upright positions around the edges of said raft, spacing the edges of adjacent panels apart, placing sheet piles in said spaces to connect adjacent panels, and then driving all of said sheet piles.

13. The method of forming a structure in water

which consists in floating a raft upon said water, forming a plurality of panels of connected sheet piles, securing a bar to each panel to cause it to conform to an edge of a part of said raft, placing said panels in upright positions in contact with the edge portions of said raft to which they conform, spacing said panels apart by detachable spacing means, removing said spacing means and inserting sheet piles to connect adjacent panels, removing said bars, and then driving all of said sheet piles.

14. The method of forming a structure in water, which consists in floating upon the water a raft having opposite outwardly curved sides conforming to the desired curvature of one unit of the

finished structure and having transversely extending end surfaces corresponding to the desired form of the ends of said unit, forming a series of panels of connected sheet piles, placing said panels in upright positions around the edges of said raft, spacing the edges of adjacent panels apart, placing sheet piles in said spaces to connect adjacent panels, then driving all of said sheet piles to form the walls of a unit of said structure, then removing said raft and placing it 5 with one of its transverse end surfaces engaging one of the transverse end walls of said unit, and then repeating the foregoing operations to form the walls of another unit of said structure.

AUGUST H. HAUSLER. 15
